**TOY LOCOMOTIVE CAB CONTAINED MOTOR
AND RELAY**

Raymond E. Smith, Hamden, Conn., assignor to The A. C. Gilbert Company, New Haven, Conn., a corporation of Maryland

Application July 30, 1954, Serial No. 446,820

9 Claims. (Cl. 46—244)

This invention relates to apparatus for effecting remote control of toy electric motors that are reversible in running direction by electromagnetic switching of circuits in their system of electric power supply. The present improvements particularly concern the control of propulsion motors of a type suitable for propelling miniature locomotives of toy trains and for use in other small electrically animated toys where space is at a premium.

It has been customary to place an electromagnetic switch or relay, for stopping, starting and/or reversing the direction of running of the propulsion motor of a toy train, in some piece of rolling stock of the train such as the tender that is separate and distinct from the locomotive. This objectionably requires that flexible circuit leads extend visibly from the motor in the locomotive to the tender. It also sometimes necessitates that the tender as well as the locomotive be equipped to collect electric current through its wheels from the track rails.

One object of the present improvements is to incorporate a controlling relay for starting, stopping and/or reversing a toy locomotive propulsion motor directly inside the locomotive in close proximity to the propulsion motor.

Another object is to attain maximum simplicity and compactness of structure in an electrically cooperative motor and controlling relay combination by mounting the motor controlling relay directly on the stator of the motor in a manner to form a unified though dividable composite structure.

Another object is so to position the unified motor and relay structure that the relay is presented in an exposed and easily accessible location at the rearwardly facing open end of the locomotive cab.

Another object is to equip the propulsion motor of a toy train with a built-in or built-on motor controlling, electromagnetic, relay switch that effects changes in the motor circuit at each cutoff and/or restoration of current to the train track from which both the motor and the relay derive cooperative electrical energization.

Further objects are so to consolidate a remote control or relay switch with its controlled motor that certain parts of the relay most likely to need servicing or replacement are readily accessible without disturbing other parts of the unit.

The foregoing and other advantages of the improvements will be apparent from the following description of illustrative embodiments of the invention having reference to the accompanying drawings wherein:

Fig. 1 is a fragmentary side view of the cab section of a toy electric locomotive with its casing shell broken away to expose a unified arrangement of propulsion motor and controlling relay incorporating the invention.

Fig. 2 shows the motor controlling relay as viewed in Fig. 1 drawn on an enlarged scale.

Fig. 3 is a view looking from the right at Fig. 2.

Fig. 4 is a view looking from the right at Fig. 3.

2

Fig. 5 is a plan view of the relay shown in Figs. 2, 3 and 4.

Fig. 6 is a view taken in section on the plane 6—6 in Fig. 3 looking in the direction of the arrows.

Figs. 7 and 8 are perspective views of the frame and magnet core, respectively, of the relay.

Fig. 9 is a diagram of electrical connections.

In Fig. 1, the hollow casing of the toy locomotive is shown broken away at 12 supported upon a chassis 13 in which are journaled the driving wheels 14 of the locomotive. In most respects the locomotive may be constructed in detail as shown in fuller detail in U. S. Patent No. 2,610,438.

As most clearly shown in Fig. 1 herein, the armature 15 of the locomotive propulsion motor 16 has a power shaft 17 worm-threaded at 18 to mesh drivingly with a worm wheel 19 fast to the axle 20 of at least one of the driving wheels 14. The stator of motor 16 carries the usual field winding 25.

According to the present improvements the stator 24 of motor 16 includes a body 23 of insulative material comprising a fixed section of the motor stator and which may incorporate a bearing bushing 22 for one end of the motor shaft 17. The insulative body 23 of stator 24 carries the sub-frame of a motor controlling relay which in Fig. 1 is designated 27 as a whole. In Figs. 1 through 8 the sub-frame of the relay comprises a bracket 28 shown detached in Fig. 7 which may be formed as an integral piece of bent sheet metal having a cross bar portion 29 spanning a space between two upright side portions 30 and 31. The left side portion 30 of bracket 28 contains a slanting notch 32 and the right side portion 31 carries a lug 33 in which there is a corresponding slanting notch 34. Notches 32 and 34 serve as bearings 35 in which are respectively journaled the trunnion ends of an axle 38 carrying an electric circuit controlling contact drum 39.

The stationary core 40 of an electromagnet 41 is formed by one downward extending leg or branch of an integral F-shaped block 44 of suitable magnetizable material such as a molded body of sintered iron mix shown in detail in Fig. 8. Another leg 45 of block 44 parallels and is spaced laterally from core leg 40 in offset relation thereto and carries at its bottom end a hinge pin 46 on which there is rockably supported the mounted end of an armature 56 of the electromagnet 41. Block 44 is fixedly attached to frame bracket 28 by means of a mounting screw 42 that extends horizontally through the former and into threaded engagement with a tapped hole in the cross bar 29 of bracket 28. This bracket itself is fixedly mounted on the insulative body 23 of stator 24 by means of a mounting protrusion formed by its forwardly bent-over lug 43 secured by the screw 53.

Surrounding and fitting core 40 there is a spool 47 comprising a hollow upright barrel 48 of insulating material that may be molded integrally with top and bottom spool heads 49 and 50, respectively. The top spool head 49 has an upward extending flange 51 penetrated by the aforesaid mounting screw 42 whereby to hold the spool in fixed relation to core 40. A conventional solenoid winding 52 is carried on the core spool 47.

Armature 56 of electromagnet 41 comprises a rocker bar 57 having hinge lugs 58 that are swingably mounted on the aforementioned hinge pin 46. This armature may be made of magnetic ingot iron and carries a patch plate 59 of the same material in position to be attracted by the magnetic field at the bottom end of core leg 40. Plate 59 is prevented from coming into actual contact with this core leg by the head of a non-magnetic brass rivet 60.

The free end 61 of armature bar 57 rises and falls responsively to magnetic energizing and deenergizing of

core leg 40. Its free end is narrowed and loosely engages in an aperture 65 through the bottom end portion of a vertically shiftable plate pawl 66 wherefore to actuate the latter. Pawl 66 is guided in its vertical reciprocative movement by extending through a narrow space adjacent the left side portion 30 of bracket 28 afforded by ears 67 that are offset from the sheet metal of the bracket. Midway its vertical length pawl 66 further is guided to sway in up and down movements by means of a suitably shaped aperture 68 therein whose edges are engaged by the shank of a stationary guide stud 69 fixed in the bracket side 30 and having an enlarged head that overlaps and constrains the pawl 66.

The top arcuate tip 64 of pawl 66 is adapted to engage successively with consecutive teeth on a ratchet wheel 74 in a manner to pock the latter step-by-step in increments of rotation. Each reciprocation of pawl 66 thus causes a one-eighth revolution of the ratchet wheel. Ratchet wheel 74 is fastened on one of the trunnion ends of axle 38 of the contact drum 39 so that each upward stroke of the armature 56 likewise rotates drum 39 one-eighth of a revolution. An auxiliary extension or check finger 70 on pawl 66 serves as a click by engaging with a tooth on ratchet wheel 74 different from that tooth which is being poked by pawl tip 64 thereby to prevent the pawl advanced rotary parts from overrunning the designed increment of rotation as shown in the broken line position of the pawl in Fig. 2.

Circuit switching contact drum 39 has a core 75 of insulative material, such as any suitable molded plastic, that is made fast to the drum axle 38 and is grooved in regions of its periphery to be fitted thereto with three commutator segments. Two of these segments comprise hollow conductive end caps 76 in permanent electrical connection with axle 38 and each castellated in an axial direction to present at the peripheral surface of the drum core diametrically opposite contact faces 76 staggered apart at ninety degrees circumferential spacing about the periphery of the drum. The third or intermediate commutator segment 77 is a tubular element that sleeves over the insulative drum core and presents four contact faces extending alternately in opposite axial directions and spaced apart ninety degrees circumferentially and located centrally between the four contact faces afforded jointly by the two end caps 76 so as to interdigitate therewith in completely insulated relation thereto.

Contact drum 39 is rotated step-by-step and lightly wipes past the drum contacting ends of three stationary conductive brushes 78, 79 and 80 which may comprise spring leaves of beryllium copper. Brushes 78 and 80 are alike and bear against the drum near their upstanding free ends. A mid portion of each of the spring leaves 78 and 80 is clamped between the aforesaid upstanding insulative flange 51 of solenoid spool 47 and a terminal base block 81 comprising an angular body of molded insulation that is penetrated by the same mounting screw 42 that extends through the solenoid core block 40 and spool flange 51. The bottom ends of spring leaves 78 and 80 project to form binding post 86 and 87, respectively, for electrical connections hereinafter referred to.

The third or central brush 79 is secured by a rivet or eyelet 83 on a shelf portion of the terminal base 81. This brush constitutes a spring leaf of conductive metal which slants upward from the terminal base 81 to bear on the commutator drum 39 at a point displaced circumferentially 45 degrees from the points on the drum where the brushes 78 and 80 make contact. A laterally extending tongue 84 forms a part of the spring leaf 79 that projects laterally beyond the terminal base 81 to serve as a binding post for electrical connection hereinafter referred to.

Under the head of screw 42 there also is clamped a conductive terminal bar 82 that projects laterally beyond the terminal base block 81 to serve as a binding post affording anchorage for electrical connections hereinafter referred to.

4

A current supplying conductive leaf spring 85 removably mounted on relay frame 28 bears constantly against and in electrical contact with a trunnion end 38 of the metallic drum axle 20 and releasably retains the axle rotatably journaled in the frame bracket bearing notches 32 and 34 while placing the axle in constant electrical connection with relay frame 28. Figs. 3, 4 and 5 best show the disposition and removable mounting of spring leaf 85 on the frame bracket 28.

For disabling the action of armature 56 at will, the outboard end 62 of its bar 57 is engageable by a stop arm 89 that is swingably mounted on leg 92 of frame bracket 28 by means of a pivot stud 90 and frictionally stayed by spring washer 91 in or out of a position to block the armature against magnetically urged movement as shown in full lines and broken lines, respectively, in Fig. 4.

The operation is conveniently understood by reference to the wiring diagram of Fig. 9 wherein electric current is assumed to be derived by the locomotive carried equipment from the track rails 21 in any one of several known manners. From one of the track rails 21 current is conducted by suitable insulated leads, not shown in Figs. 1 to 7, to one armature brush of motor 16 and also to one end of the winding 52 of solenoid 41. The other armature brush of motor 16 is electrically connected to the spring leaf 79 at the latter's binding post terminal 84 which spring leaf is constantly in electric contact with commutator segment 77. One end of the motor field winding 25 is electrically connected to spring leaf 78 at the latter's binding post terminal 86 and the other end of the motor winding is electrically connected to the spring leaf 80 at the latter's binding post terminal 87. The other one of the track rails 21 is electrically connected by conductive leads, not shown in Figs. 1 to 7, to the binding post terminal 82 that is grounded to the relay frame 28 through the medium of screw 42 and to the other end of the winding 52 of the solenoid 41. Certain of the mechanical parts represented in Fig. 9 bear the same reference numerals as they do in other figures of the drawings.

With the above understanding of the electrical connections and assuming that the commutator drum 39 is in such rotary position that the spring leaves 78 and 80 are both in contact with that insulative surface 75 of the drum that intervenes between the conductive drum segments 76 and 77, obviously no current can flow through the motor because the circuits containing spring leaves 78, 79 and 80 are all dead ended. At all times, however, the winding 52 of solenoid 41 is in circuit across the track rails 21, 21. Therefore so long as the track is electrically energized, solenoid 41 maintains its armature 56 lifted to its broken line position in Fig. 3 where it remains until current is cut-off from the track.

When current is cut-off from the track solenoid 41 is deprived of current and its armature 56 together with pawl 66 falls by gravity to the full line position in Fig. 3 whereupon the actuating finger 64 of pawl 66 drops to its full line position in Fig. 2 ready to engage the next tooth 32 of ratchet wheel 74 when pawl 66 is next lifted. This occurs whenever current is restored to the track rails 21, whereupon solenoid 41 is energized and its armature 56 attracted upward. This causes pawl 66 to rotate the commutator drum 39 one-eighth of a full turn which brings one or another of the commutator segments 76 into contact with spring leaf 78 or 80 respectively. This furnishes current to the motor armature through leaf spring 85 and 79 through the medium of segment 77 and simultaneously furnishes current through one or another of the commutator segments 76 to the motor winding 25 through the leaf spring 78 or 80 depending upon the rotary position of drum 39.

Thus it will be seen that at each quarter turn of the commutator drum current passes through the motor field winding in alternately reverse directions which causes the

motor to run alternately in reverse directions of rotation after the commutator drum in each case has passed through an intervening step of commutator rotation wherein no current at all is supplied to the motor.

The consequent operative effect upon the running of the train is that step-by-step rotary advance of the commutator drum causes the following sequence of effects upon the propulsion motor 16: —stops train—runs train forward—stops train—runs train backward. This sequence of current controlling action of the relay continues ad infinitum and serves to determine whether the train shall run forward or backward or shall be brought to a stop merely by alternately cutting-off and restoring current to the track rails.

I claim:

1. The combination of, the cab portion of a toy locomotive having a rearwardly directed opening, a propulsion motor sharing the space in said cab portion having an armature shaft extending forward and aligned axially with said opening, and an electromagnetic relay sharing said space in said cab portion located at said opening, comprising a relatively thin assembled unit having its length and breadth disposed athwart the axis of said shaft for compacting the combined space consuming bulk of said motor and said relay lengthwise the locomotive, said unit incorporating an electromagnet and movable contacts mechanically connected to be shiftable thereby and electrically connected to vary circuits through which said motor is energized.

2. The combination defined in claim 1, in which the said relay unit includes a conductive mounting protrusion, together with a motor stator encompassing the said armature shaft incorporating an insulative body on which said mounting protrusion is supported and by which said protrusion is insulated from the motor stator.

3. The combination defined in claim 2, together with fastening means detachably holding the said relay unit to the said motor stator.

4. The combination defined in claim 2, together with fastening means detachably holding the said mounting protrusion to the said insulative body.

5. The combination defined in claim 1, in which the

said assembled unit of the said electromagnetic relay includes a skeletonized subframe of conductive metal and an electromagnet flanked on three sides by said subframe and supported thereby.

5. The combination defined in claim 5, together with current switching conductors including a commutator drum rotatably carried by the said subframe adjacent to one axial end of the said electromagnet including circuit shifting contacts in constant electrical connection with said subframe.

6. The combination defined in claim 6, in which the said commutative drum has a conductive axle journaled in the said subframe and constantly in electrical connection therewith and also with the said circuit shifting contacts to afford the said electrical connection between said contacts and said subframe.

7. The combination defined in claim 7, in which opposite sides of the same subframe have open ended bearing notches in which the said conductive axle is removably journaled.

8. The combination defined in claim 8, together with a conductive spring leaf mounted on the said subframe and wipingly bearing on the said axle in a direction releasably retaining said axle in at least one of the said bearing notches.
